(57) **CLAIM**

The ornamental design for a light emitting diode panel with a track for a spotlight, as shown and described.

DESCRIPTION

FIG. 1 is a perspective view of a first embodiment of a light emitting diode panel with a track for a spotlight according to the principles of the present invention;

FIG. 2 is a right side view thereof;

FIG. 3 is a rear view thereof;

FIG. 4 is a bottom view thereof;

FIG. 5 is a perspective view of a second embodiment of a light emitting diode panel with a track for a spotlight according to the principles of the present invention;

FIG. 6 is a right side view thereof;

FIG. 7 is a rear view thereof; and,

FIG. 8 is a bottom view.

The portions shown in dash-dot broken lines including a spotlight form no part of the claimed design.

The portions shown in dot-dash-dot lines represent boundaries between claimed and unclaimed subject matter.

1 Claim, 8 Drawing Sheets
